UNITED STATES PATENT OFFICE.

FRANK CONRAD, OF SWISSVALE, PENNSYLVANIA, ASSIGNOR TO WESTINGHOUSE ELECTRIC AND MANUFACTURING COMPANY, A CORPORATION OF PENNSYLVANIA.

ELECTRICAL REGULATOR.

1,122,693.

Specification of Letters Patent. Patented Dec. 29, 1914.

Application filed October 5, 1911. Serial No. 652,865.

To all whom it may concern:

Be it known that I, FRANK CONRAD, a citizen of the United States, and a resident of Swissvale, in the county of Allegheny and State of Pennsylvania, have invented a new and useful Improvement in Electrical Regulators, of which the following is a specification.

My invention relates to electrical regulators, and it has for its object to provide a simple and effective regulator of the kind in which the regulation is effected by adjustment of the field excitation of a dynamo-electric machine.

15 My invention is illustrated in the accompanying drawing, the single figure of which is a diagrammatic view of a system of distribution embodying the same.

As illustrated, a system in connection with 20 which the present invention may be conveniently employed comprises a main generator, the armature 1 of which is connected to a suitable circuit 2—3—4 and the field magnet winding 5 of which is supplied with 25 exciting current from the armature 6 of an exciter. The exciter is provided with a field magnet winding 7 that is shunt excited, or supplied with current from any other suitable source, and in series with which is a 30 resistor 8 that is adapted to be shunted by a pair of coöperating stationary and movable contact terminals 9 and 10 of a relay 11. The relay is provided with another pair of 35 coöperating stationary and movable contact terminals 12 and 13, and the movable contact terminals 10 and 13 are actuated by a winding 14 that is supplied with current from the exciter and the circuit of which is governed in a manner to be hereinafter 40 more fully explained. The relay is provided with a second winding 15 that is permanently connected to the exciter and is arranged in opposition to the winding 14. When the winding 15 is energized alone, the 45 contact terminals 10 and 13 are thereby maintained out of engagement with the corresponding stationary terminals 9 and 12 against the tension of a spring 11^a, but when both of the windings 14 and 15 are energized 50 their magnetizing effects neutralize each other and the spring 11^a then separates the said terminal members.

The circuit of the winding 14 is controlled by a pair of coöperating stationary 55 and movable contact terminals 16 and 17,

the stationary terminal 16 being mounted upon one end of a spring 18 or being otherwise resiliently supported. The contact terminal 17 is carried by one end of a lever 19 from the other end of which is suspended a core 60 20 that is surrounded by an actuating winding 21 and is partially counter-balanced by an adjustable counter weight 22. The winding 21 receives energy that is proportional to the voltage of the distributing circuit 2—3—4 and accordingly varies the position of the contact terminal 17 in response to variations of the said voltage.

65 The contact terminals 12 and 13 control the circuit of an electromagnet winding 24 having a core 25 that is carried by a lever 26 and the movements of which are preferably retarded by means of a dash pot 27. The winding 24, when energized, serves to draw the core 25 downwardly against the tension 70 of a spring 28. The lever 26 is connected to the lever 19 by means of a retarding device or dash pot 29.

75 In the operation of the regulator, the distance of the movable contact terminal 17 from the terminal 16 is varied in response to fluctuations of the voltage of the circuit 2—3—4 by means of the winding 21, and the said contact terminal is moved into and out of engagement with the contact terminal 16 80 by means of the magnet winding 24 which is alternately energized and deenergized by reason of the engagement and disengagement 85 of the relay contact terminals 12 and 13.

90 Variation of the distance of the contact terminal 17 from the terminal 16 is effected by the winding 21 while, at the same time, it is vibrated into and out of engagement with the terminal 16, by reason of the dash pot 95 29 between the levers 19 and 26, the two relatively movable members of the dash pot being caused to occupy varying positions with respect to each other by the winding 21. The dash pot is preferably so adjusted 100 that a continuously applied force, such as that produced by the winding 21, will cause relative movement between the two parts thereof, but so that intermittently applied forces, first in one direction and then in the 105 other, such as are produced by the winding 24 will cause no permanent relative displacement of the said parts. Thus, the periods of engagement and disengagement of the contact terminals 16 and 17 are varied 110

in response to the voltage of the distributing circuit and, through the relay contacts 9 and 10, the excitation of the field of the exciter is so governed as to properly compensate for any deviations of the voltage from its normal value.

Since the present regulator operates to effect the desired regulation by adjustment of the field excitation of the generator, it is evident that it may be employed for regulating in accordance with variations of the electrical condition of a generator or circuit other than the voltage by simple and obvious changes of the connections of the winding 21, or by the substitution therefor of other suitable means for varying the position of the contact terminal member 17, all within the spirit of the present invention.

I claim as my invention:

20 1. An electrical regulator comprising co-operating contact members, two actuating devices for one of them, and a yielding connection between one of said devices and the actuated contact member having a time-element function.

25 2. An electrical regulator comprising co-operating contact members, a lever carrying one of said members and having an actuating winding, a second lever having an actuating winding, and a yielding connection between the said levers having a time-element function.

30 3. The combination with a dynamo-electric machine and a circuit connected thereto, of a regulator for the dynamo-electric machine comprising a contact member, two actuating windings for the contact member energized from said circuit, and a yielding

connection through which one of said windings actuates the contact member having a time-element function.

4. The combination with a dynamo-electric machine and a circuit connected thereto, of a regulator for the dynamo-electric machine comprising a contact member, two actuating windings for the contact member energized from the said circuit, a yielding connection through which one of said windings actuates the contact member having a time-element function and relay mechanism controlled by said contact member and in turn controlling both the excitation of the dynamo-electric machine and the energization of the latter winding.

5. In an electrical regulator, the combination with co-operating contact members, and two actuating devices for one of them, of a connection between one of said devices and the actuated contact member comprising relatively movable parts that are retarded in their relative movements.

6. In an electrical regulator, the combination with co-operating contact members, a lever carrying one of said members and having an actuating winding, and a second lever also having an actuating winding, of a connection between said levers comprising relatively movable parts that are retarded in their relative movements.

In testimony whereof, I have hereunto 70 subscribed my name this 29th day of Sept., 1911.

FRANK CONRAD.
